United States Patent [19]

Kuo

[11] Patent Number: Des. 401,696

[45] Date of Patent: **Nov. 24, 1998

[54] ELECTROMAGNETIC WAVE GENERATOR

[76] Inventor: Su Jong Kuo, P.O. Box 63-99,
Taichung, Taiwan

[**] Term: 14 Years

[21] Appl. No.: 65,107

[22] Filed: Jan. 21, 1997

[51] LOC (6) Cl. 24-01

[52] U.S. Cl. D24/200

[57] CLAIM

The ornamental design for an electromagnetic wave generator, as shown and described.

DESCRIPTION

FIG. 1 is a perspective view of an electromagnetic wave generator showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
